HUMPTY DUMPTY RACER TOY

Paul L. Luzius, Brentwood, Tenn., and Jerrold J. Krumholz, West Orange, N.J., assignors to Kusan, Inc., Nashville, Tenn.

Filed May 22, 1973, Ser. No. 362,656

Term of patent 14 years

Int. Cl. D21—01

U.S. Cl. D34—15 AN

FIG.1

FIG. 1 is a front elevational view of the humpty dumpty racer toy showing our new design;

FIG. 2 is a side elevational view thereof;

FIG. 3 is a rear elevational view thereof; and

FIG. 4 is a top plan view thereof.

We claim:

The ornamental design for a humpty dumpty racer toy, as shown.
